Primary Examiner — Elizabeth J Oswecki*Assistant Examiner* — Lacey Chey Bowman(74) *Attorney, Agent, or Firm* — Buchanan Ingersoll & Rooney PC(57) **CLAIM**

The ornamental design for a dashboard camera as shown and described.

DESCRIPTION

FIG. 1 is a perspective view of a dashboard camera showing my new design;

FIG. 2 is a front view thereof;

FIG. 3 is a rear view thereof;

FIG. 4 is a right view thereof;

FIG. 5 is a left view thereof; and,

FIG. 6 is a top view thereof.

The portions of the dashboard camera shown in broken lines are for illustrative and environmental purposes and form no part of the claimed design.
